UNITED STATES PATENT OFFICE

141,320

DESIGN FOR A TOY SINK

Joseph Brunetti, Carlstadt, N. J., assignor to
Columbia Protektosite Co., Inc., Carlstadt,
N. J., a corporation of New Jersey

Application December 19, 1944, Serial No. 116,998

Term of patent 7 years

(Cl. D34—15)

To all whom it may concern:

Be it known that I, Joseph Brunetti, a citizen of the United States and resident of Carlstadt, in the county of Bergen and State of New Jersey, have invented a new, original, and ornamental Design for a Toy Sink, of which the following is a specification, reference being had to the accompanying drawing, forming a part thereof, and of which Figure 1 is a front view of a toy sink showing my new design; Fig. 2 is a top view thereof; Fig. 3 is a side view thereof; and Fig. 4 is a bottom plan view of the same on a reduced scale.

The dominant features of the design reside in

the toy sink shown having a drainboard and a sink at different sides, a tier of horizontal drawers beneath the drainboard and a pair of vertical doors beneath the sink, said tier and doors extending for substantially the full height of the article, a series of horizontal spaced lines immediately below the drainboard and sink, and the abbreviated representations of a faucet and its handles.

I claim:

The ornamental design for a toy sink, substantially as shown and described.

JOSEPH BRUNETTI.
